UNITED STATES PATENT OFFICE

96,379

DESIGN FOR A COMBINED COUCH AND PILLOW

Harry I. Freedman, Chelsea, Mass., assignor to New York Mattress Company, Boston, Mass., a corporation of Massachusetts

Application March 23, 1935, Serial No. 56,019

Term of patent 7 years

To all whom it may concern:

Be it known that I, Harry I. Freedman, a citizen of the United States residing at Chelsea in the county of Suffolk and State of Massachusetts, have invented a new, original, and ornamental Design for a Combined Couch and Pillow, of which the following is a specification, reference being had to the accompanying drawing, forming part hereof, which is a perspective view of the article, showing my design.

I claim:

The ornamental design for a combined couch and pillow as shown.

HARRY I. FREEDMAN.
